The ornamental design for a ceiling fan blade, as shown and described.

DESCRIPTION

FIG. 1 is a top plan view of a ceiling fan blade showing my new design;

FIG. 2 is a bottom plan view thereof;

FIG. 3 is a right side elevational view thereof;

FIG. 4 is a left side elevational view thereof;

FIG. 5 is a right end elevational view thereof; and,

FIG. 6 is a left end elevational view thereof.

The broken line showing of blade irons in FIGS. 1-6 is for illustrative purposes only, and forms no part of the claimed design.

The fragmentary criss-cross pattern shown in FIGS. 1-6, is understood to be repeated throughout the blade panel.
